GEORGE W. CLAYTON AND JOHN MORRISON, OF SHARON, PENNSYLVANIA.

CHECK-PROTECTOR.

1,267,744.

Specification of Letters Patent. Patented May 28, 1918.

Application filed February 20, 1918. Serial No. 218,275.

To all whom it may concern:

Be it known that we, GEORGE W. CLAYTON and JOHN MORRISON, citizens of the United States, residing at Sharon, in the county of 5 Mercer and State of Pennsylvania, have invented certain new and useful Improvements in Check-Protectors, of which the following is a specification.

This invention relates to hand stamps, and 10 more especially to check punches; and the object of the same is to produce an improved check protector capable of being carried in the pocket or in the baggage, and occupying very little space in or on the desk.

15 A primary object of the invention is inexpensiveness and simplicity, while sacrificing nothing in efficiency. Details are set forth in the following specification, and reference is made to the accompanying drawings, wherein:

Figure 1 is a perspective view of this device in use;

Fig. 2 is a plan view with the upper portion removed;

25 Fig. 3 is an enlarged cross section on the line 3—3 of Fig. 2, with the cover in place.

In the drawings the numeral 1 designates a base to one end of which at the point 2 is hinged the upper portion or cover 3, an 30 opening or slot 4 being provided between the hinges for the insertion of the check indicated by the letter C. Both the base and the cover may be box-like members as seen in Fig. 3 preferably stamped from light sheet 35 metal and suitably ornamented, and the parts may be of appropriate size excepting that the slot 4 should be large enough to receive an ordinary check or draft.

Within the base and near the hinged end 40 thereof is disposed a feed roller 10 having its surface roughened in any suitable way as indicated at 11 and one of its trunnions carries an exterior knob 12 by means of which this roller may be turned. Also mounted in 45 the base adjacent the feed roller is a die roller 13 carrying thereon at an appropriate point a ring of letters or characters which are raised so as to constitute a male die 14 capable of impressing a letter, character, 50 figure or the like into the check C being treated; and one of the trunnions of this roller carries a knob 15 which is preferably marked with letters or characters corresponding with those on the die. Hinged or 55 otherwise movably connected at 16 with the cover 3 is an arm 17 extending transversely

across the cover at a point above the die roller 13 and having a knob or handle 18 at its free end. Beneath this knob the arm carries a point 19 projecting downward through 60 a hole 20 in the top of the cover and constituting the platen in that it co-acts with the die to produce a character on the check being treated. The construction of parts is such that when the knob 18 is struck by the hand 65 of the operator, the platen descends through the hole and drives the check onto one of the characters or letters in the die 14. To operate this device, the cover 3 is preferably raised on its hinges 2 and the check or draft 70 laid across the die roller at a point where the inscription is to be impressed upon or into it with the left end of the check over the feed roller 10 and perhaps carried out through the slot 4. The cover is now closed 75 down, leaving a little of the check protruding as seen in Fig. 1. The knob 15 is manipulated to bring the proper character at the top, and a sharp blow on the knob 18 impresses this character on the check. The latter is now drawn to the left slightly without changing the position of parts, after which the knob 15 is reset to bring the second character under the platen and the knob 18 is given another blow; and so on until the 80 proper word is written on the check or the proper amount punched or impressed thereon in case the characters and the knob 15 bear figures rather than letters as shown. When the feed roller 10 is employed, the 85 check may be moved step by step to the left by turning the knob 12 in the proper direction, and we prefer to use this feed roller as shown. The active face of the dies may be such as will impress the letter or character 90 into the check or such as will perforate the same or perhaps cut out the same; we lay no claim to this detail and reserve the broadest latitude with respect to the same and to other details not brought out in the following 95 claims.

What is claimed as new is:

1. In a check protector, the combination of a box-like casing comprising a base and a cover hingedly connected at one end and 105 having a slot between the pair of hinges, the cover having a hole at a proper point, a die rotatably mounted in the base under said hole, means for manually setting said die, an arm carried by the cover, and a platen carried by the arm and standing within said hole, for the purpose set forth.

2. In a check protector, the combination of a box-like casing comprising a base and a cover hingedly connected at one end and having a slot between the pair of hinges, the 5 cover having a hole at a proper point, a die roller rotatably mounted in the base and having a ring of dies under said hole, means for manually setting said roller, a feed roller rotatably mounted in the base between said 10 die roller and slot and having a knob on one of its trunnions, and a platen movably carried by the cover and adapted to be driven through said hole, for the purpose set forth.
- 15 3. In a check protector, the combination with a box-like casing having a slot in one end and a hole in its top, and a knob mov-

ably mounted on said top and having a platen projecting through the hole; of a die rotatably mounted within the casing beneath said hole and having characters adapted to come under the same, a knob on its trunnion exterior of the casing and bearing corresponding characters, a feed roller rotatably mounted within the casing between said die and slot, and a knob on one of its trunnions.

In testimony whereof we affix our signatures in presence of two witnesses.

GEORGE W. CLAYTON.
JOHN MORRISON.
